**DATA STORAGE CASSETTE FOR ACOUSTIC
COUPLING OF INFORMATION**

**John P. Kennedy, 2198 Woodstock Road,
Columbus, Ohio 43215**

Filed Apr. 20, 1972, Ser. No. 246,109

Term of patent 14 years

Int. Cl. D14—03

U.S. Cl. D26—14 A

FIG. 3

FIG. 1

FIG. 2

FIG. 4

FIG. 5

FIG. 6

FIG. 1 is a top plan view of a data storage cassette for acoustic coupling of information;

FIG. 2 is a side view of the tape cassette of FIG. 1;
FIG. 3 is another side view of the tape cassette of FIG. 1;

FIG. 4 is a rear view of the tape cassette of FIG. 1;
FIG. 5 is a bottom plan view of the tape cassette of FIG. 1; and

FIG. 6 is a front view of the tape cassette of FIG. 1.

I claim:

The ornamental design for data storage cassette for acoustic coupling of information, as shown and described.
